UNITED STATES PATENT OFFICE

2,313,919

ELECTRICAL VIBRATOR DEVICE

Alexander D. Burt, Haddon Heights, N. J., assignor to Radio Corporation of America, a corporation of Delaware

Application February 9, 1939, Serial No. 255,396

3 Claims. (Cl. 200—90)

The present invention relates to an electrical vibrator device adapted generally for converting low voltage direct current into high voltage direct current for radio power supply and the like.

Vibrator devices of this type are well known in connection with radio receivers and like apparatus, particularly for use in automobiles and localities where the power supply is limited to a low voltage battery, and may comprise a suitable electromagnetic actuating means for a vibratory armature carrying contacts for interrupting the current supply and rectifying the secondary voltage in connection with a power supply transformer.

It is an object of the present invention to provide an electrical vibrator device of the type referred to, having an improved construction adapted for operation under varying conditions and applications.

It is also an object of the present invention to provide an improved vibrator unit which permits rectification of relatively high voltages and relatively high power without increasing the rate of contact deterioration.

It is a still further object of the invention to provide an improved electrical vibrator unit which is adapted for use in aircraft, and the like, for operation at varying altitudes without being subject to violent sparking and other disadvantages which become apparent ordinarily at higher altitudes because of the reduced air pressure.

It is also a still further object of the present invention to provide an improved electrical vibrator system which permits the use of a relatively small power transformer in connection therewith and a relatively small and low cost electric filter for the electrical output therefrom.

To prevent contact deterioration, the entire unit may be mounted in a vacuum so that there may be no gas to ionize at the contacts, or the unit may be enclosed in a casing containing gas under pressure, that is, above atmospheric pressure, whereby the power handling contacts may be operated at higher voltages without increasing the air-gap between the contacts beyond a certain limit at which the width of the air-gap begins to interfere seriously with the operation of the device.

However, in accordance with the invention the vibrator contacts are enclosed with vacuum or pressure chambers in pairs to prevent contact arcing and deterioration and at the same time to eliminate the necessity for enclosing the entire device within a sealed chamber. This also permits the removal of the contacts in the form

of cartridges which are replaceable in the unit as required.

The problem of reducing the size of the apparatus required is met by increasing the frequency of the vibrator operation whereby the operating frequency is increased and such a frequency is chosen that will allow a relatively small power transformer and audio filter to be employed in connection with the vibrator device. At the high frequency the mechanical gap between the various contacts may be relatively small even when the voltage across a given gap is increased to a relatively high value.

With the contacts enclosed, the problem of varying altitude and external air pressure is obviated and by utilizing an inert gas under pressure in each contact chamber the problem of heat conduction and arcing at the contacts is reduced.

The invention will be further understood from the following description when considered in connection with the accompanying drawing, and its scope will be pointed out in the appended claims.

In the drawing,

Figure 1 is a schematic view in elevation with certain parts in cross section and on an enlarged scale, of an electrical vibrator device embodying the invention.

Figure 2 is a top view of the device of Fig. 1 provided with a schematic circuit diagram showing connection for the contacts with a power transformer, and

Figure 3 is a view in cross section and on an enlarged scale of a modification of the contact elements of the device of Figs. 1 and 2.

Referring to Figs. 1 and 2, 5 is a vibratory flat spring armature element fixedly mounted at one end 6 and having a suitable armature shoe 7 at the opposite end thereof and is caused to vibrate between positions 8 and 9, shown dotted lines.

The actuating means for vibrator devices of this type are well known and usually comprise electromagnetic means for influencing the armature shoe and a contact element for intermittently energizing the electromagnetic means. Accordingly, the actuating means per se which may be of any suitable type, has been omitted for the reason that it does not form part of the present invention.

It is essential that the armature element be relatively short and have a relatively high frequency or short period of vibration. For example, 500 to 2000 cycles per second may be suitable and in comparison with the present known

vibrator devices having a frequency of the order of 60 to 100 cycles per second, the frequencies referred to are relatively high.

The armature element 5 is arranged to actuate the contacts of the vibrator device and any suitable number of contacts may be employed in connection therewith. In the present example four sets of contacts are shown. These are provided in sealed cartridges indicated at 10, 11, 12 and 13 and are preferably individually releasably mounted in suitable sockets or retaining members 14 positioned to hold the contact cartridges in spaced relation to the armature element on opposite sides thereof as shown. The contacts may thus be removed and replaced as a unit when renewal is necessary.

In one embodiment of the invention, the cartridges are tubular and arranged as shown, substantially coaxially in pairs on opposite sides of the armature element and with the inner ends presented toward the armature element sealed by flexible diaphragms 15 each carrying a movable contact element 16 on the inner face and engaging on the outer face with an actuating finger 17 of flexible spring material secured at one end to the armature as indicated at 18. The contact cartridges are each provided with an interior chamber 19 containing an inert gas such as nitrogen under pressure and is sealed at the rear or outer end by an insulating plug 20 which may be of glass or other suitable insulating material having a central opening in which an electrical terminal member 21 for a fixed contact 22 is sealed.

The contact 22 is positioned adjacent to the contact 16 and the latter is moved into engagement with the contact 22 by action of the armature applying pressure through the finger 17 as the armature moves in the direction of the contact cartridge.

The diaphragm 15 while providing a seal for the pressure chamber, is flexible and permits the contact action to take place and at the same time supplies the retracting force for separating the contacts.

The fingers 17 are preferably in the form of flexible flat springs which exert a sufficient pressure when the armature is in a position of equilibrium to balance the force of the gas pressure within the chambers and to cause the diaphragm and the contacts to maintain a normal unflexed position, as shown.

The electrical circuit provided in connection with the four pairs of contacts provided in the vibrator device of the present example, may be arranged for high voltage power supply for radio apparatus from a low voltage supply as illustrated in Fig. 2, to which attention is now more particularly directed.

Referring to Fig. 2, the armature element carrying the shoe 7, is preferably grounded, as indicated at 25, and each of the four inner insulated contacts are connected with a power transformer 26 to interrupt the primary current and to rectify the secondary voltage.

For this purpose the outer terminals of the primary winding 27 are connected with the fixed contacts of the contact cartridges 10 and 11 as shown and the primary center tap 28 is connected to the low voltage battery source represented at 29. The latter may be a six-volt storage battery, for example, and is connected at the opposite terminal to ground, as indicated at 30, whereby the primary circuit is completed through the armature and the contact elements carried by

the flexible diaphragms of the cartridges 10 and 11, the connection between the armature and the diaphragms being completed through the flexible spring members 17.

As the armature vibrates each half of the primary winding 27 is energized alternately with the other half from the power source 29 and causes an alternating voltage to be set up across the secondary 31.

The secondary alternating current voltage is rectified by the contact elements 12 and 13 which are connected with the secondary terminals as shown. The secondary center tap 32 is connected with the high voltage output circuit 33.

A filter choke coil 34 is provided between the circuit 33 and the center tap 32 and suitable filter capacitors 35 are also provided in a conventional filter. However, because of the relatively high frequency, the filter capacitors 35 may be of the order of one microfarad as compared with the usual capacity of from 10 to 20 microfarads ordinarily provided in circuits of the type shown.

The contact cartridges may be made in any suitable form, for example, a form of cartridge 25 may be provided as shown in Fig. 3, to which attention is now directed, wherein the diaphragm 15 is welded to the casing 18 at one end thereof as in the embodiment shown in Figs. 1 and 2, while the rear end of the casing is closed by a glass envelope 38. The envelope is sealed about the terminal connection 21 and an inner sleeve or cup 39 is provided for receiving a screw-threaded shank 40 for the inner contact 22, whereby the air-gap may be adjusted in production and set to an exact value.

The chamber of the cartridge may be evacuated or may be filled with air or gas under pressure. Preferably a gas under pressure is utilized for the reason that heat conduction is improved and oxidation of the contacts is prevented in the same manner as it would be in the vacuum. Furthermore, for aircraft operation the varying air pressure does not appreciably change the gap adjustment and does not in any way increase the sparking as with open contacts.

With an inert gas such as nitrogen under pressure, the mechanical gap between the contacts may be made relatively small as is necessary for a high frequency vibrator, while at the same time the output voltage is not limited by the air gap since a gap which ordinarily would break down at a predetermined voltage in air will break down at a much higher voltage with an inert gas under pressure. Thus, the arrangement shown permits high frequency voltage operation to be obtained and the transformer 26 of Fig. 2 may be made relatively small in size since it operates at a relatively high frequency.

I claim as my invention:

1. A high frequency vibratory contact device for synchronous multiple circuit current interruption, comprising in combination, a spring armature element fixedly mounted at one end and proportioned to vibrate at the opposite free end with a short period, tubular contact cartridges mounted substantially coaxially in pairs on opposite sides of the armature element and containing inert gas under pressure, spring actuating members carried by the armature, one for each contact cartridge, a diaphragm at one end of each cartridge engaged and operated, and held substantially unflexed when said armature is at rest in a position of equilibrium, by one of said spring actuating members, said spring mem-

bers exerting sufficient pressure on said diaphragms to substantially balance the pressure exerted by said gas, and contacts sealed in said cartridges in pairs and operatively responsive to movement of the diaphragm.

2. A high frequency vibratory contact device for synchronous multiple circuit current interruption, comprising in combination, a spring armature element fixedly mounted at one end and proportioned to vibrate at the opposite free end with a short period of the order of 500 to 2,000 cycles per second, tubular contact cartridges mounted substantially coaxially in pairs on opposite sides of the armature element and containing inert gas under pressure, spring actuating members carried by the armature, one for each contact cartridge, a diaphragm at one end of each cartridge engaged and operated, and held substantially unflexed when said armature is at rest in a position of equilibrium, by one of said spring actuating members, said spring member exerting sufficient pressure to substantially balance that exerted on said diaphragm by said gas, contacts sealed in said cartridges in pairs and operatively responsive to movement of the diaphragm, means for engaging and holding the

contact cartridges at one end, means for insulating one of each pair of contacts from the armature element and cartridge casing, and means including the spring members for connecting the other of said contacts in each pair to the armature.

3. A high frequency vibratory contact device for circuit current interruption, comprising in combination, a pair of contacts for interrupting current, means providing an individual sealed casing for each of said contacts and containing inert gas under pressure, each of said casings having a flexible wall connected with one of said contacts within the casing, means for detachably mounting said casings in opposed spaced relation to each other, and a high frequency vibratory armature having flexible spring elements carried by the armature, one for each of said contacts, each of said spring elements bearing against the flexible wall of each of said casings for actuating said contacts, said spring elements exerting a pressure against said walls sufficient to balance the gas pressure exerted upon said walls when said armature is in a position of equilibrium.

ALEXANDER D. BURT.
